UNITED STATES PATENT OFFICE.

OSCAR ANTON WIBERG, OF FINSPOONG, SWEDEN.

BACK-PRESSURE OR NONCONDENSING STEAM TURBINE.

Application filed July 16, 1926, Serial No. 122,834, and in Sweden August 15, 1925.

This invention relates to the back-pressure or non-condensing type of steam turbines and more particularly to turbines of said type having blade wheels rotating in opposite directions. As compared with the usual type of turbine, working condensing, a pressure above condenser pressure exists in the steam outlet and, consequently, also a higher temperature.

10 The object of this invention is to prevent heat from being transmitted from the outlet of the turbine to the turbine bearings and to the electrical generators, or other machines coupled to the turbine, to an extent that 15 would cause damage to such machines.

To this end, the steam chests of the turbine are connected to or formed integral with an inner turbine casing, preferably provided with ventilation means, said inner 20 casing being in turn surrounded by an outer turbine casing through which circulation of air may take place.

In the drawing Fig. 1 is a vertical longitudinal section of a turbine embodying the 25 invention and,

Fig. 2 is a side elevation, partly in cross section, of the turbine.

The blade system 1 of the turbine and the associated parts are mounted in a casing 30 comprising two vertically arranged plates each having an inner or central flat portion 2, on which said system is mounted, and an outer dished shaped portion 3 surrounding the central portion. These outer portions 35 are formed with peripheral flanges 4 connected together by bolts or rivets 5. Said plates have a spiral periphery as shown in Fig. 2 so that the dished portions 3 form a substantially annular chamber 6 surrounding the blade system and a conduit 7 for the 40 exhaust steam. That part of the casing forming the chamber 6 has an insulating covering 8, and if desired the latter may cover the discharge conduit. The whole inner casing 45 is enclosed in a casing 9 hereinafter referred to as the outer casing, said outer casing being spaced from the inner casing so as to form a free space 10 around the inner casing. Openings 11 are formed in the outer casing 50 to permit circulation of air in said space and permit the outer casing 9 to be maintained at a temperature sufficiently low to prevent expansions and stresses that may act detrimentally.

55 The steam chests 12 and the steam admission passages 13, which communicate with

the blade system 1 are connected to or, as shown in Fig. 1, formed integral with the inner turbine casing. As in the casing of turbines that work condensing the outer casing 9 supports the bearings 14, 14 and forms a bed frame 15.

The inner casing surrounding the blade system receives the exhaust steam and is so constructed and arranged as to prevent those expansions to which it is subjected, due to the high temperature of the exhaust steam, from having any disadvantageous effect on adjacent parts. To this end, the walls of the chamber 6 are formed resilient inasmuch as their thickness is so chosen as to keep the value of the axial thrust, due to heat expansion, within moderate limits. In order to prevent the formation of rust on the inner turbine casing said casing is provided with ventilation valves or cocks 16 which are held open when the turbine is at rest to permit the circulation of air through the interior of the turbine whereby the system will be kept dry. These valves may be of any type desired, provided they are of sufficient size to permit proper ventilation. In actual use an opening is provided in the turbine casing controlled by a screw cover.

What I claim is:

1. In a non-condensing steam turbine of the type having blade wheels rotating in opposite directions, the combination of steam chests, an inner casing surrounding the blade wheels, and connected to the walls of said steam chests, ventilation means on said casing, and an outer casing surrounding said first mentioned casing so as to leave a free space therearound, said outer casing having holes formed in it to permit circulations of air in said space.

2. In a non-condensing steam turbine of the type having blade wheels rotating in opposite directions, the combination of steam chests, separate members of resilient material connected to the walls of said steam chests and to each other so as to form an inner turbine casing, ventilation means on said casing, and an independent outer turbine casing surrounding said first mentioned casing so as to form a free space therearound, said outer casing having holes formed in it to permit circulation of air in said free space.

3. In a non-condensing steam turbine of the type having blade wheels rotating in opposite directions, the combination of steam

chests, a stationary casing surrounding the blade wheels and connected to the walls of said steam chests, ventilation means on said casing, an insulating covering on the outside 5 of said casing, and an independent outer casing supporting bearings for the turbine and forming the bed-frame thereof, said outer casing surrounding said first-mentioned casing so as to form a free space 10 therearound and having holes formed in it to permit circulation of air in said space.

4. In a non-condensing steam turbine of the type having blade wheels rotating in opposite directions, the combination of steam 15 chests, an inner casing surrounding the blade

wheels and forming the exhaust chamber of the turbine, said inner casing being connected to the walls of said steam chests, ventilation means on said inner casing, an insulating covering on the outside of said 20 casing, and an independent outer turbine casing supporting bearings for the turbine and forming the bed-frame thereof, said outer casing surrounding said first-mentioned casing so as to form a free space 25 therearound and having holes formed in it to permit circulation of air in said space.

In testimony whereof I have signed my name.

OSCAR ANTON WIBERG.
